UNITED STATES PATENT OFFICE.

JACOB A. HYLE, OF ST. LOUIS, MISSOURI, AND JACOB W. HERMAN, OF PHILADELPHIA, PENNSYLVANIA, ASSIGNORS TO TRI-CITY STEEL COMPANY, OF ST. LOUIS, MISSOURI, A CORPORATION OF DELAWARE.

METALLIC RAILWAY-TIE.

1,296,396.

Specification of Letters Patent.

Patented Mar. 4, 1919.

Application filed October 29, 1917, Serial No. 199,045. Renewed January 23, 1919. Serial No. 272,779.

To all whom it may concern:

Be it known that we, JACOB A. HYLE and JACOB W. HERMAN, citizens of the United States, residing at St. Louis, State of Missouri, and in the city and county of Philadelphia and State of Pennsylvania, respectively, have invented certain new and useful Improvements in Metallic Railway-Ties, of which the following is a specification.

10 Our invention relates to the construction of metallic railway ties and means for securely fastening the track rails in proper position on the ties of steam and electric railways.

15 The prime object of the invention is to provide an economical, strong, durable and efficient metallic railway tie and rail fastening means possessing the required strength to readily withstand all the usual strains to which the tie and rail fastening means are normally subjected when in use and which are so constructed as to materially increase the longevity of the same.

Another object of our invention is to provide a metallic railway tie in connection with wooden blocks constituting a resilient support for the track rails, and a safe and reliable insulation of the rails so that said rails will serve as efficient conductors in the 25 usual automatic signaling systems.

A further object of this invention is to so construct our improved railway tie that the number of ties required per mile of road bed will be materially reduced.

30 Still further objects of the invention are to so construct the tie that the wooden blocks utilized in connection therewith may be easily and readily removed and a new block replaced by one employee and without removing the tie, or in any manner disturbing the position of the track rail or ballast beneath the tie; to safely and firmly secure the wooden blocks to the tie, thereby maintaining absolute safety in the gage of 35 the track rails, and to secure the track rails in their proper position upon the wooden blocks by the means of the ordinary railway spike now in use and employed in most all railways for the purpose of securing the 40 track rails to a wooden tie, and to provide improved means forming a portion of the tie for preventing the wooden blocks from

spreading apart under the strains to which they are subjected.

The foregoing and such other objects as 55 may appear from the ensuing description are attained by the means hereinafter more fully described, and by the combination, construction, arrangement and location of the parts such as illustrated in the accompanying drawings and particularly pointed out in the claims appended hereto, it being understood that slight changes in the form proportions, and minor details of the construction may be resorted to without departing 60 from the spirit or sacrificing any of the advantages of the invention.

In the accompanying drawings which form a part of the specification it will be seen that:

70 Figure 1, is a side elevation of the improved railway tie and rail fastening means embodying our invention, showing the track rails in cross-section secured thereto.

Fig. 2 is a perspective view of the metallic 75 tie proper with the track rail supporting and securing means removed therefrom.

Fig. 3, is an end elevation with the track rail omitted.

Fig. 4, is a plan view of a portion of the 80 metallic tie, and

Fig. 5, is a face view of the inner surface of one of the wooden block securing plates, and

Fig. 6, is a side or edge elevation of the 85 same.

Similar numerals of reference are employed to designate corresponding parts throughout the several figures of the drawings.

90 In carrying out our invention, we provide a railway tie of suitable or desirable dimensions throughout its length and breadth and the metallic portion of said tie with which our invention is embodied in 95 the form illustrated may be made from any suitable metallic material, but is preferably made from cast-off or worn-out steel railway rails by cutting through the web of the rail immediately below the tread portion, and 100 then rolling the web and base portion thereof into the form illustrated in the drawings, which comprises a flat laterally extended base portion 1, and a central vertical mem-

ber 2, extending throughout the entire length of the tie, each end of said central member being downwardly and outwardly inclined at 3.

- 5 It will be perceived that the track rails 4 are not supported directly on the metal portion of the tie, but are seated and rest upon the upper surface of the wooden blocks 5, there being two blocks on each side of the 10 central vertical member of the tie, and two blocks near each end of the tie, each block having smooth straight vertical faces and resting upon the upper surface of the laterally extended base portion of the tie, the upper 15 surface of each block projecting a suitable distance above the vertical portion of the tie in order to effectually insulate the track rails from the tie, and to form a wide bearing surface at the upper portion thereof 20 of for the base of the track rail. The size of the blocks is sufficient to furnish the required strength to support the track rails and retain the rail fastening means such as plain spikes such as are ordinarily used for 25 securing the track rails to a wooden tie, which spikes are driven into the wooden blocks with the head portion of each spike overlapping and in contact with the upper surface of the base of the rail.
- 30 The wooden blocks 5, are first preferably impregnated with crude oil or creosote to increase their durability and are formed rectangular in cross-section, and adapted to fit accurately upon the base portion and against 35 the central vertical member of the tie, the dimensions of the blocks being uniform so that they may be turned upside down or either side may be utilized as the top or track-rail supporting surface.
- 40 The fastening means preferably employed for firmly and securely clamping each block to the body portion of the tie consists of two headed bolts 6, screw-threaded at one end thereof, two clamping plates 7, which extend 45 from the top to the bottom of the block, and two securing nuts 8, each bolt passing through the opening in the block and the opening 9 in the central member of the tie, whereby the blocks, tie and clamping plates 50 are all securely locked together by the said bolts 6, and the securing nuts 8 fitted to the threaded end of each bolt and resting in contact with the outer surface of each clamping plate 7.
- 55 It will be observed that each of the clamping plates 7 is provided on its inner face with an elongated vertically arranged lateral extension 10, above and below the central opening 11, which extensions are adapted 60 to enter and become embedded into the outer side face of each block, thereby preventing any vibratory or swinging movement of the blocks or the plates when the parts are securely locked together, and the 65 clamping plates embrace the outer side wall

of each block the entire height of the block in order to prevent the splitting of the said block.

In order to insure safety by preventing the spreading apart of the wooden blocks in the event the securing bolts shall become broken or impaired, we stamp up from the base portion of the tie a plurality of vertical or upright integral extensions 12, each extension being so located as to rest in contact 75 with the outer end surface of each block, thus serving to prevent the outward movement of the blocks, and the base portion of the tie is provided with a recessed central portion 13 extending substantially the entire 80 distance between the blocks, thus economizing in the amount and cost of material employed and also furnishing more convenient and accessible means for tamping up the ballast arranged around the ties, further, to 85 prevent the tie from becoming center-bound.

While we show the base of the track rail seated upon the upper surface of the wooden blocks, it will be obvious that any suitable or desirable plate may be utilized to rest 90 upon the blocks and thereby form a seat for the track rail base.

It will be readily perceived that each wooden block projects above the metal portion of the tie, thus constituting an insulating medium and preventing interference with the use of electric signaling means, and the laterally extended base portion of the tie upon which the wooden blocks are supported forms a widened tie, thus materially reducing 95 the number of ties per mile of road bed as are usually required, and it is more readily retained in place than the narrower ties.

It will also be seen that each block being provided with two openings therethrough 105 and the openings in the central vertical member of the metal tie, that when the clamping plates are secured to the outer side wall of each block by the fastening bolts and nuts the fiber of the wooden blocks will 110 become tightly compressed and prevented from splitting when the rail fastening spikes are driven therein, and the blocks will be held securely in contact with the base of the tie, thus preventing any up and down movement from the said base with the wave motion of the rail during the passage of the rolling stock over the track rails, and there can be no shifting of the blocks without moving the entire tie and track rail supporting means, thereby insuring and always maintaining the proper gage of the track rails and alignment of the track.

It will be understood that the space between the wooden blocks and at the outer end of said blocks is filled up with track ballast which assists in preventing any lateral, longitudinal or skidding action of the railway ties during the strains to which they are usually subjected.

The wooden blocks such as utilized are inexpensive, since the ends of logs and other pieces of wood are used up which would ordinarily be classed as waste material.

5 Having thus described our invention, what we claim and desire to secure by Letters Patent is:—

1. A metallic railway tie comprising a flat base portion having a central recess at 10 each side thereof, a central vertical member inclined outwardly at each end, two wooden blocks resting upon the base at each side for supporting the track rails, means for securing said blocks to the tie, means for securing 15 the track rails to the blocks, and a plurality of integral vertical extensions stamped from the base of the tie and resting in contact with the outer end face of each block.

2. A metallic railway tie comprising a flat base portion provided with a central recessed portion at each side thereof, a central integral vertical member, two wooden blocks resting upon the base at each side, securing bolts passing through each block and said 25 central member, a plurality of metallic plates fastened at each side of the outer side face of each block, a securing nut fastened to the threaded end of each bolt, and a plurality of integral vertical extensions 30 stamped from the base of the tie.

3. A metallic railway tie comprising a flat base portion having a central recess at each side, a central integral vertical member,

two wooden blocks resting upon the upper surface of the base at each side of said central member, securing bolts passing through the said blocks and central member, metallic plates fastened to the outer side face of each block extending the entire height of the block, a securing nut fastened to the threaded end of each bolt resting in contact with the outer face of each metallic plate, and a plurality of integral vertical extensions stamped from the base of the tie and resting in contact with the outer end face of each block. 35

4. A metallic railway tie comprising a flat base portion having a central recess at each side thereof, a central integral vertical member, two wooden blocks resting upon the upper surface of said base at each side of the central member and projecting above said central member, means for securing said blocks to the tie consisting of securing bolts passing through each block and the central member, a plurality of metallic plates having an extension on each inner face adapted to be embedded into the block when secured thereto, a securing nut fastened to the threaded end of each bolt, means for securing the track rails to said blocks, and a plurality of integral vertical extensions stamped from the base and adapted to contact with the outer end face of each block. 50 55 60
